UNITED STATES PATENT OFFICE.

ROBERT THOMAS MULLINS, OF BROOKLYN, NEW YORK, ASSIGNOR TO A. G. SPALDING & BROS., OF NEW YORK, N. Y., A CORPORATION OF NEW JERSEY.

GOLF BAG.

Application filed June 2, 1926. Serial No. 113,117.

This invention relates to caddy bags and aims to improve the construction and widen the utility of such bags.

An object of the invention is to provide a reversible bag formed of a single piece of flexible material. One side of the bag is provided with pockets for carrying golf clubs and other equipment and it is intended to normally have this side exposed while playing on the links. The reverse side of the material is continuous and unbroken and is adapted to serve as a cover for the bag during transportation. A slide-actuated interlocking fastener is attached to the free edges of the flexible material and is adapted to hold the edges together in either position of the bag. This fastener also provides means for completely closing and locking the bag when it is in covered position. A single handle is attached to both sides of the material at points directly opposite and has its loop passed through a slot in the material. It is thus possible to slide the handle through the slot and use it with the bag in either position. The shoulder strap is similarly arranged and is also capable of double duty.

While a preferred embodiment has been disclosed for purposes of illustration it should be understood that various changes can be made in the structure without departing from the spirit and scope of the invention as hereinafter described and claimed.

35 In the drawings:

Fig. 1 is a perspective of the bag in playing position with the pocket side exposed;

Fig. 2 is an elevation partly in section showing the bag in position for traveling;

Fig. 3 is a plan view of the bag opened out flat and showing the pocket side;

Fig. 4 is a fragmentary perspective showing the bottom of the bag in the closed position of Fig. 2.

Referring to the drawings more specifically, the body 10 of the bag is a piece of flexible material such as canvas shaped as shown in Fig. 3. A small rectangular piece 50 of material 11 is laid across the body near the upper end of the body and is stitched thereto at its lateral edges and along the longitudinal seams 12. A second piece of material 13 is laid across the lower part of the body and is also stitched to the bag

along its edges and along seams 12. Cross seams 14 and 15 also help to tack the piece 13 to the main body. This structure provides two longitudinal pockets 16 and 17 along the edges of the body. The piece 11 forms a septum dividing the upper end of each of these pockets 16 and 17 and projecting above these pockets, and also forms a shallow pocket 18 for carrying balls and other small articles. A pocket 19 is formed in the center of the lower part of the body, and is closed by a buckled flap 20.

A leather reinforcing member 21 is fastened to each side of the body near the center and just below seam 14. The shoulder strap 22 passes through a slot 23 cut through the upper part of the reinforcing members 21, and has its ends secured to antipodal points on the lower part of the reinforcing members. A handle 24 is similarly arranged near the center of the reinforcing strips.

The lower edge of the bag is reinforced by a leather binding 25 and metal corners 26. The interlocking members 27 of the fastener extend from the point of a curved notch formed in the upper margin of the body, along each side of the body and curve inwardly above the metal corners and terminate near the center of the lower edge. A slide 28 is provided for operating the fasteners in a well-known manner.

When the bag is to be used for carrying clubs on the links the body is folded along the center line with the pocket side out. The slide 28 is operated to fasten the edges of the bag together and the bag is then in the position of Fig. 1. The iron clubs can be placed in the pockets 16 and 17, while the wooden clubs can be placed behind the 95 septum 11, thereby isolating them from the iron clubs.

When it is desired to use the bag for transporting clubs, the slide 28 is first pulled to release the fasteners 27, the bag is opened out flat and then folded in reverse position with the cover side of the body out. The slide 28 is now operated to close the fasteners 27 with the bag in the position of Fig. 2. In this position the fasteners can be used to completely close all open sides of the bag, and a hasp 29 secured to the slide 28 can be locked to a staple 30 secured to the body.

It will be evident from Fig. 2 that both the handle and the shoulder strap can be 110

slid through the slots to be used with the bag in either of its operative positions.

When the bag is being carried on the links in the position of Fig. 1 and rain begins to fall, the bag can be instantly reversed to the position of Fig. 2, the fasteners being closed only over the curved top of the bag, thereby forming a hood to protect the clubs but leaving the front side open for easy access to the clubs.

While I have disclosed the invention as applied to a caddy bag it will be evident that certain features of the invention are capable of adaptation wherever a reversible bag of the type disclosed would be useful.

I claim:—

1. A bag comprising a reversible body of flexible material and a slide actuated interlocking fastener adapted to secure edges of the body together in either position of the body.

2. A golf bag comprising a reversible body of flexible material having pockets formed on one of its sides, the reverse side forming a covering side, and means to secure edges of the body together with either side turned out.

3. A bag comprising a reversible body of flexible material, and a handle passing through a slot in the body and attached to opposite parts of the body.

4. A bag comprising a reversible body of flexible material, a handle passing through a slot in the body and attached to antipodal parts of the body, and a shoulder strap passing through a slot in the body and attached to opposite parts of the body.

5. A bag comprising a reversible body of flexible material, a handle passing through

a slot in the body and attached to antipodal parts of the body, and a shoulder strap passing through a slot in the body and attached to opposite parts of the body and surrounding the handle.

6. A bag comprising a reversible body of flexible material, a piece of material secured to the body and forming pockets, and a second piece of material extending into one of the pockets to form a septum and secured to the body beyond the first piece of material.

7. A bag comprising a reversible body of flexible material, having a pocketed side and a covering side, a slide actuated interlocking fastener adapted to secure edges of the body together with either side turned out, and a handle secured to the body in a manner rendering it available in either position of the bag.

8. A bag comprising a reversible body of flexible material, having a pocketed side and a covering side, a slide actuated interlocking fastener adapted to secure edges of the body together with either side turned out, a handle and a shoulder strap both of which are secured to the body in a manner rendering them available in either position of the bag.

9. A bag comprising a reversible body of flexible material having a pocketed side and a covering side, a slide actuated interlocking fastener adapted to secure all free edges of the body together with either side turned out, and means for locking the slide when the bag is in closed position.

In testimony whereof I affix my signature.

ROBERT THOMAS MULLINS.
